PRACTICAL PAPER PERFORATOR

James Gasio, Los Angeles, Calif.

Application June 23, 1945, Serial No. 601,221

9 Claims. (Cl. 164—91)

1

The invention pertains to an improvement in perforators for paper and the like characterized by a novel arrangement of base, punches and operating levers whereby efficient operation may be had with an economy both of space required and material employed in the construction.

Heretofore perforators such as are commonly employed for perforating papers to accommodate filing devices have been characterized by a relatively wide and heavy base to serve as a support during operation of a punch operating lever disposed above and extending generally transversely to a plane containing the axes of the spaced punches.

It is an object of the present invention to provide a perforator in which the operating means for the punches extends parallel to a plane containing the axes of the punches whereby the necessity of a large clumsy base element is dispensed with.

Another object of the invention is to provide a perforator in which the supporting means for the levers, and the punches as well as the cooperating die means associated with the punches is formed from a single piece of metal.

A still further object of the invention is to provide a perforator having a pair of spaced punches and an operating lever for each punch in which the operating levers are so arranged relative to one another that they may be operated singly or in unison as may be desired.

A still further object of the invention is to provide a perforator in which the base or frame element is formed of a single piece of sheet metal.

Still another object of the invention is to provide a perforator having a one-piece frame structure which is so shaped as to provide a stop element to determine the position of the perforations relative to the edge of the paper.

With the foregoing objects in view, together with such other objects and advantages as may subsequently appear, the invention resides in the parts and in the combination, construction and arrangement of parts hereinafter described and claimed, and illustrated by way of example in the accompanying drawing, in which—

Fig. 1 is a front elevation partly in section of an illustrative embodiment of a perforator embodying the principles of my invention,

Fig. 2 is a top plan view of the perforator shown in Fig. 1, and

Fig. 3 is a staggered sectional, end elevation, taken generally along the line 3—3 of Fig. 1.

In general in the form illustrated, the base comprises a sheet metal base member 1 of modi-

2

fied S-shape configuration, said base being provided with a pair of levers 2, 2 hinged at 5, 5 to opposite ends of the base and adjacent their hinge points, the levers engage the ends of punches 3, 3 guided in the base member 1 and normally held out of engagement with their cooperating die apertures by compression springs 4, 4 surrounding the punches and extending between the base member 1 and U-shaped collars 6, 6 on the punch members; each of said collars engaging grooves 6a, 6a on the punches and being held therein by the pressure exerted thereagainst by the springs 4, 4. The free ends of the levers extend downwardly through an opening 7 in the base member and thence are reversely bent to engage the opposite surface of the base member whereby the extent of their outward travel induced by the springs 4, 4 and the punches 3, 3 is limited.

Referring now more specifically to the illustrated embodiment of the invention, the base member 1 comprises a piece of sheet metal bent into a modified S-shape and including a lateral run 9, at each end of which spaced tongue elements 10, 10 are downwardly and upwardly bent to form stationary hinge pin holding elements, a vertical run 11, a second lateral run 12 disposed parallel to the run 9 and spaced therefrom, a second vertical run 13 and a third lateral run 14 extending parallel to the lateral runs 9 and 12 and relatively closely spaced to the run 12. Extending in axial alignment through the lateral runs 9, 12 and 14 and adjacent the ends thereof are holes 9a, 12a and 14a and 9b, 12b and 14b which holes are of the same diameter. Slidably mounted in the holes 9a and 12a and 9b and 12b respectively are the punch elements 3, 3 surrounded by a compression spring 4, 4 extending between the surface of the run 12 and the U-shaped collars 6, 6 hereinbefore referred to. As shown in Fig. 1 the collars 6b are so positioned on their respective punches that when the collars are in engagement with the face of the run 9; the ends of the punches will be positioned in the run 12 but will not protrude into the space between the runs 12 and 14. At the same time the opposite rounded ends of the punches extend through the run 9 to engage the operating levers 2, 2 each of which levers at one end is bent as at 15 to provide a means to engage hinge pins 16, 16 held in the holding elements 10. The levers at their other ends are provided with rebent portions 17, 17 which extend through the opening 7 in the run 9 and which rebent portions engage the surface of the run 9 to serve as stop means limiting their movement.

The holes 14a and 14b serve as the cooperating dies for the punches 4, 4.

In use, the paper is inserted in the slot formed by the lateral runs 12 and 14 until the edge engages the wall formed by the vertical run 13 and is then shifted sidewise until centered or otherwise positioned after which pressure is applied to either or both levers with resultant production of one or two perforations. Preferably the punches will be spaced to accommodate standard filing devices but it will be appreciated that by the simple expedient of having the punches independently operable that other spacings can be achieved or, where only a single perforation is required, that result can be had without the unnecessary punching of another hole or perforation as is the case with perforators constructed to make two or more perforations simultaneously by manipulation of a single means.

In this connection it is to be noted that the free ends of the operating levers are disposed sufficiently closely to each other so that the finger of an operator cannot enter therebetween incident to the simultaneous operation thereof. Also since they are close to each other they may be simultaneously operated as easily as though only a single lever were involved.

Furthermore, attention is again directed to the fact that the levers are disposed parallel to a plane containing the axes of the punches instead of being lateral thereto whereby a very narrow base element can be employed.

Still further, it is to be noted that the frame element may be conveniently formed from a single substantially rectangular sheet of metal formed into a shape not requiring expensive tooling to fabricate nor which involves any waste of material. Additionally, the other component parts are of equally simple design and are equally susceptible of economical manufacture.

While I have shown and described a specific embodiment of my invention, I do not limit myself to the exact details of construction set forth, and the invention embraces such changes, modifications and equivalents of the parts and their formation and arrangement as come within the purview of the appended claims.

I claim:

1. In a perforator, a frame member of modified S-shape configuration comprising top, intermediate and lower lateral runs separated by vertical runs, a pair of perforating elements guided for reciprocation in said top and intermediate runs, die elements in said bottom run cooperating with said perforating elements, and a pair of levers pivoted to said top run constructed and arranged to operate said perforating elements.

2. In a perforator, a frame member of modified S-shape configuration comprising top, intermediate and lower lateral runs separated by vertical runs, a pair of perforating elements guided for reciprocation in said top and intermediate runs, die elements in said bottom run cooperating with said perforating elements, and a pair of levers pivoted to said top run constructed and arranged to operate said perforating elements, said levers being disposed for oscillating in a plane parallel to and containing the axes of said perforating elements.

3. In a perforator, a frame member of modified S-shape configuration comprising top, intermediate and lower lateral runs separated by vertical runs, a pair of perforating elements guided for reciprocation in said top and intermediate runs, die elements in said bottom run cooperating with

said perforating elements, and a pair of levers pivoted to said top run constructed and arranged to operate said perforating elements simultaneously or separately at the will of the user.

5. In a perforator, a frame member of modified S-shape configuration comprising top, intermediate and lower lateral runs separated by vertical runs, a pair of perforating elements guided for reciprocation in said top and intermediate runs, die elements in said bottom run cooperating with said perforating elements, and spring means associated with each of said perforating elements operable normally to hold said perforating elements out of engagement with said die elements.

15. In a perforator, a frame member of modified S-shape configuration comprising top, intermediate and lower lateral runs separated by vertical runs, a pair of perforating elements guided for reciprocation in said top and intermediate runs,

20. die elements in said bottom run cooperating with said perforating elements, spring means associated with each of said perforating elements operable normally to hold said perforating elements out of engagement with said die elements and

25. means for operating said perforating elements simultaneously or separately at the will of the user.

6. In a perforator for paper and the like, a sheet metal base member bent to form three parallel portions separated by web portions disposed at right angles to said parallel portions, a lever hinged to one of said parallel portions, a perforating element guided for reciprocation in said parallel portion and in the next adjacent portion and disposed adjacent to said lever for engagement with and operation thereby, a die in said third parallel portion disposed in cooperative relation to said perforating element and spring means normally operative to maintain said perforating element out of engagement with said die.

7. In a perforator for paper and the like, a sheet metal base member bent to form three parallel portions separated by web portions disposed at right angles to said parallel portions, a lever hinged at one end to one of said parallel portions, means operative to limit the extent of travel of the other end of said lever away from said one of said portions, a perforating element guided for reciprocation in said parallel portion and in the next adjacent portion and disposed adjacent to said lever for engagement with and operation thereby, a die in said third parallel portion disposed in cooperative relation to said perforating element and spring means normally operative to maintain said perforating element out of engagement with said die.

8. A perforator for paper and the like comprising a frame member bent to form three spaced parallel elements of substantially identical outline, a perforating element guided for reciprocatory movement in the intermediate and in one of the outer of said parallel elements, a die in the other of said parallel elements adapted to cooperate with said perforating element, spring means normally operative to hold said perforating element and said die spaced from each other, and a manually operable lever of the second order hinged to said frame element engageable with said perforating element and adapted to move it into engagement with said die element with resultant perforation of a sheet of paper or the like placed therebetween.

9. A perforator for paper or the like comprising a frame having a die portion provided with a pair of spaced die openings therein, a pair of perforat-

ing elements, said frame having a guide portion in which said perforating elements are mounted in vertical alignment with said die openings, spring means operative normally to maintain said perforating elements out of engagement with said die openings and operating means for said perforating elements comprising a pair of levers fulcrumed at one end about parallel spaced axes on said frame, the effective ends of said levers as regards to leverage being disposed in such close relation to one another that said levers may be actuated simultaneously with two fingers held close together.
